CLAIM

The ornamental design for an upper body garment, as shown and described.

DESCRIPTION

FIG. 1 is a front elevational view of an upper body garment showing my new design;

FIG. 2 is a rear elevational view of the upper body garment;

FIG. 3 is a right side elevational view of the upper body garment;

FIG. 4 is a left side elevational view of the upper body garment;

FIG. 5 is a top plan view of the upper body garment; and,

FIG. 6 is a bottom plan view of the upper body garment. The details shown in broken lines in FIGS. 1 and 2 are for illustrative purposes only and form no part of the claimed invention.
